CLAIM

The ornamental design for a device for temporarily holding a live pig, as shown and described.

DESCRIPTION

FIG. 1 is a front elevational view of a device for temporarily holding a live pig in a folded configuration;

FIG. 2 is a front elevational view thereof; showing only the right wing in a folded position;

FIG. 3 is a top plan view thereof, showing the design in an unfolded configuration; and,

FIG. 4 is a top plan view thereof, showing the only the left wing in a folded position.
